UNITED STATES PATENT OFFICE

EINAR M. ARENTZEN, OF FRANKLIN, PENNSYLVANIA, ASSIGNOR TO JOY MANUFACTURING COMPANY, OF FRANKLIN, PENNSYLVANIA, A CORPORATION OF DELAWARE

ARTICULATED CONVEYER

Application filed December 26, 1928. Serial No. 328,500.

This invention relates to a conveyer organization of the endless belt type, the frame of which comprises two longitudinally aligned, articulated abutting sections one of 5 which sections is adapted to have horizontal, radial swing or adjustment relative to the other; the traveling, material-actuating mechanism is of the endless chain and scraper type which is adapted to actuate material in continuous, uninterrupted movement 10 over both sections of said conveyer.

The object of this invention is, to supply 15 a conveyer having a receiving end or section, comprising a stationary frame for the reception of material, goods or merchandise of nearly any description and a delivery section having a free end which may be moved horizontally through an arc of at least 90 degrees in extent and deliver its load continuously along said arc or at any desired point 20 or points thereof.

The construction whereby I am enabled 25 to attain said object is clearly illustrated in the drawings which constitute a portion of this specification and in which:

Fig. 1 is a plan view of my improved conveyer in which the movable section is shown as being flexed to the left.

Fig. 2 is a side elevation of said conveyer.

Fig. 3 is a longitudinal section of a portion of the receiving end of the frame.

Fig. 4 is a transverse section on line IV—IV of Fig. 2.

Fig. 5 is a plan view of the articulated, 35 flexible area of the conveyer.

Fig. 6 is an end view of the adjacent end of Fig. 5.

Fig. 7 is a central, longitudinal section of Fig. 5.

Fig. 8 is a plan view of the joint castings for the deck of the frame.

Fig. 9 is a central, longitudinal section of Fig. 8.

Fig. 10 is a plan view of the joint castings 45 or hinge of the floor of said frame.

Fig. 11 is a central, longitudinal section of Fig. 10.

Fig. 12 is a plan view partly in section with other parts broken away of an assembly 50 unit of the conveyer chain.

Fig. 13 is a side view of an arm link of said chain showing the arm in transverse section.

Fig. 14 is a side view of one of the connecting plates for the arm links of said chain. 55

Fig. 15 is a schematic view of the hydraulic jacks whereby the swinging end of the conveyer is radially, laterally actuated, showing the control valve in horizontal section. 60

Fig. 16 is an assembly view of the fluid pump and its control valves whereby fluid under pressure is delivered to the hydraulic jacks.

Fig. 17 is a plan view of the control valves 65 shown in Fig. 16.

Fig. 18 is a horizontal section of the control valve for the vertical jack whereby the free or delivery end of the conveyer is raised and lowered. 70

The construction shown in said drawings is substantially as follows:

The frame of the conveyer comprises two sections, namely, a rigid section 1 which may be mounted upon any suitable stationary or movable support, and a horizontally swinging section 2. Each of said sections is a box like structure; said section 1 has a floor 3 and a deck 4 which are united at their edges by means of the side channels 5, 5; side flanges 6, 6 are also supplied. Section 2 comprises a floor 7 and a deck 8 which deck and floor are united at their lateral edges by means of the side channels 9, 9; side flanges 10, 10 are also supplied, all of said members being structural steel elements. 75

Said sections 1 and 2 are united by means of articulations consisting of the two hinge structures shown in Figs. 8 and 9, 10 and 11 respectively. 80

The Fig. 8 structure is attached to the under side of and unites the deck plates 4 and 8; the base member 11 is secured to the deck plate 4 and the wing member 12 is attached to the deck plate 8; the pivotal point and member of said two members 11 and 12 is indicated by the ordinal 13. 85

The Fig. 10 hinge structure is attached to and unites the floor plates 3 and 7; the base member 14 is attached to floor plate 3 and 100

the wing member 15 is attached to floor plate 7; the pivotal point and member of said Fig. 10 structure is indicated by the ordinal 16. Said pivotal points 13 and 16 are accurately 5 alined vertically as shown and indicated in Fig. 7 by the center line $c-c$.

The abutting, junctional edges of the decks 4 and 8, also the floors 3 and 7 are arcuate, the arcs being struck from the center point 10 $c-c$ on the radius R of Fig. 5. The plate 17 shown in dotted lines in Fig. 8 is firmly riveted at one end to the wing 12; the other end of said plate extends beneath the deck plate 4 and is firmly riveted thereto; the arcuate 15 portions 18 of said wing 12 are segmental, grooved pulley sections, about which pass the actuating cables whereby section 2 of the elevator frame is caused to swing radially; the junctional or abutting ends of the deck and 20 floor plates 3 and 4 are laterally widened to conform to the area that is swept over by the flexible flanges 19 and 20 when section 2 is caused to swing laterally to its respective limits of travel.

Said section 2 is actuated to its various 25 positions of radial swing by means of the following described equipment and in the following manner:

Upon each side of said section 1 is mounted 30 a hydraulic jack 21 and 22 each of which is provided with a plunger 23, 24 respectively, also a breech 25, 26; a pulley 27 and 28 is mounted in the respective breeches; pulleys 29, 30 are also mounted in the outer end of 35 the respective plungers 23 and 24; the breech blocks 25 and 26 are each provided with a cable eye 31, 32 respectively, for the attachment of the respective actuating cables 33, 34. One end of each cable 33, 34 is attached to 40 the eye of its respective jack and from thence it is passed around the plunger pulley 29, 30, thence around the guide pulley 27, 28 of said jack, thence around its respective pulley sector 18, 18 of the hinge member 12 and firmly 45 secured to said member 12.

For the purpose of actuating said jacks a pump and fluid control organization is provided comprising the following members which are shown especially in Figs. 15 to 18.

A supply of fluid—preferably oil—is carried in a tank or reservoir 35 into which is connected the suction pipe 36 of any suitable pressure pump 37. The discharge pipe of said pump is preferably divided into two 50 branches 38 and 39; branch 38 leads to a control valve 40 whereby the fluid is controlled and selectively directed to and released from either jack 21 or 22. From an inspection of Fig. 15 it will be noted that said valve 40 is supplied with two outlet pipes one of which, 44, leads into jack 21, and the other pipe 45 leads into jack 22. In said Fig. 15 the plug 43 of said valve is shown as being set for the direction of fluid through the flexible 55 pipe 44 into the jack cylinder 21, and for

the discharge of fluid from the jack cylinder 22 through the flexible pipe 45 into valve 40 and from thence into the by-pass pipe 46 which communicates with the suction pipe 36 of the pump. By imparting to said plug 70 43 substantially a quarter of a turn the fluid directing conditions above set forth may be relatively reversed as to the jacks 21 and 22, whereby the sweep of section 2 of the conveyer may be caused and determined both as 75 to direction and extent, at will. By placing said plug 43 in a position intermediate the two positions just specified, or so that the duct 46 will be in registry with duct 48, the pump 37 may operate continuously and the 80 actuated fluid will be by-passed through the by-pass 46' and pipe 46 into the suction pipe 36.

A description of the valve 47 and its function will be presently given.

Referring now to the scraper chain which actuates material along the decks 4 and 8, the members which make up an assembly unit of said chain are shown in the assembled relation in Fig. 12 and separately in Figs. 13 85 and 14.

Said chain comprises a sprocket link 48 having laterally extending arms or scrapers 49, also a sprocket link 50 which does not have the scrapers; said links 48 and 50 are provided at each end and upon each side with hooks 51, 51, for engagement with the eyes 52 of the connecting plates 53. Said arms 49 have an over-all length which is substantially equal to the width between the flanges 6—6 or 10—10 of the conveyer, and they are provided at their outer extremities with a roller 54 which may contact with the inner, adjacent, vertical face of the respective flange at the side of the deck, and when the conveyer is in the flexed position at either side of the longitudinal center line said rollers upon the corresponding ends of scrapers 49 bear heavily upon the inner face of the right hand flange 19 if the conveyer is flexed toward 100 the right, or the inner face of the left hand flange 20 if the conveyer is flexed toward the left, as shown in Fig. 1. The flanges 19 and 20 are, as previously stated, laterally flexible and are rigidly secured to the flanges 6 at the points 55, but the other end of said flanges 19 and 20 are provided at 56 with a slip joint for the purpose of providing for the difference in length caused by the longer and shorter radii of the respective sides in various conditions of flexure.

The conveyer chain is driven by the sprocket 57, Fig. 3, which is keyed to the shaft 58; said shaft 58 is directly connected and driven by the shaft 59 of the speed reducing unit 60; said unit 60 is driven by an electric motor 61; the shaft of pump 37 is directly connected to the shaft of said motor.

As shown in Fig. 4 a plain roller or pulley 62 is provided at the free end of the conveyer 130

over which the conveyer chain travels; said roller 62 is loosely, revolvably mounted upon a shaft 63 which is adapted to have motion longitudinally of the frame 2 and in such a manner that it may not only have a considerable degree of flexibility and movement responsive to severe tension upon the conveyer chain, but may also automatically act as a take-up whereby said chain may be kept taut in case of wear between the members of the links thereof. Said flexibility and automatic take-up action is secured in the following manner; a shaft 64 has an end which is reduced in diameter, and this shaft is introduced through an adjusting screw 65 and through a compression spring 66 with its reduced end occupying an eye 67 in the outer end of said shaft 63; said screw is carried in a rigid lug 68 which is provided with a cooperating screw thread; one end of said spring bears against said shaft 67 and the other end thereof against the adjacent end of said screw 65; by the adjustment of said screw, spring 66 may be caused to exert any desired amount of pressure upon said shaft 67 and at the same time said shaft is yieldably responsive to undue tension upon the chain.

The receiving end of the conveyer is hung upon shaft 58, the outer end of which shaft is provided with an outboard bearing 69. A hydraulic jack 70 also supports section 1 of said conveyer, whereby the free end of said conveyer may be adjusted vertically.

The breech of said jack is provided with a fluid inlet 71, to which is attached a flexible pipe leading from the outlet 72 of the control valve 47. This valve is shown in transverse section in Fig. 18 and from an inspection of said figure the operation of said valve will be readily understood; its principle of operation is substantially the same as that of valve 40.

Many modifications of most of the details described in the foregoing specification may be made as desired, and as illustrations of such modifications, the conveyer chain may consist of links as 48 and plates 53; the jack 70 may or may not be employed; a sector shaped rack and a cooperating pinion provided with suitable manually operative means may be substituted for the jacks 21 and 22.

I claim the following:

1. A conveyer organization employing a conveyer means of the endless type and comprising in combination a main frame for said conveyer consisting essentially of two articulated, longitudinally, alined sections with their adjacent ends in abutting relation, one of which sections is radially adjustable relative to the abutting end of the other section, a deck for said radially-adjustable section, a deck for said other section, said decks being individually integral members, a vertically-

extending flange positioned at each side of said decks and having a laterally flexible portion extending over the area of articulation of said sections, a conveyer adapted to travel over said decks longitudinally thereof and between said flanges for the conveyance of material, means for driving said conveyer and means for adjusting said adjustable section; the deck of the other section, at and adjacent the abutting end thereof, being widened so that its lateral edges are caused to extend beyond the limit of sweep of said vertically extending, flexible flanges whereby a plane surface is provided for the uninterrupted travel of material thereover when the conveyer is flexed.

2. A conveyer organization of the endless chain and scraper type comprising in combination a main frame for said conveyer consisting of two longitudinally-alined, articulated, abutting sections one of which is adapted to have horizontal, radial adjustment relative to the other section, means operable to cause such adjustment, a deck for each of said sections the adjacent abutting ends of which decks are so arranged that material may be moved uninterruptedly thereover, a vertically-disposed flange for each side of said decks each of said flanges having a laterally flexible portion extending across the articulated area of said sections, scrapers adapted to travel upon and throughout the combined length of said decks to move material thereover, an endless chain connected and transmitting motion to said scrapers and means for driving said chain.

3. A conveyer organization having a conveyer means of the endless chain and scraper type and comprising in combination a main frame consisting essentially of two articulated, longitudinally-alined, abutting sections one of which is horizontally, radially adjustable relative to the adjacent abutting end of the other section, a deck for said radially-adjustable section, a deck for said other section, the form and relative arrangement of the adjacent ends of said decks being such that material may be moved uninterruptedly thereover at any position of adjustment of said adjustable section, a vertically-extending flange positioned at each side of said decks each provided with a laterally flexible portion adjacent the area of articulation of said sections, scrapers arranged to travel upon said decks between said flanges for the movement of material, an endless chain connected to said scrapers and transmitting movement thereto, means operative to drive said chain, and means for effecting adjustment of said adjustable section.

In testimony whereof I have affixed my signature.

EINAR M. ARENTZEN.

DISCLAIMER

1,785,402.—*Einar M. Arentzen, Franklin, Pa. ARTICULATED CONVEYER. Patent dated December 16, 1930. Disclaimer filed October 29, 1938, by the assignee, Joy Manufacturing Company.*

Hereby enters this disclaimer to that part of the claims in said specification which is in the following words:

In claim 1, we disclaim

“a conveyer adapted to travel over said decks longitudinally thereof and between said flanges for the conveyance of material,”

except where said conveyer comprises a single endless chain that extends around said decks so as to lie above and below the same in a plane substantially vertical thereto.

In claim 2, we disclaim

“an endless chain connected and transmitting motion to said scrapers”

except where said chain extends around said decks so as to lie above and below the same in a plane substantially vertical thereto.

In claim 3, we disclaim

“an endless chain connected to said scrapers and transmitting movement thereto,”
except where said chain extends around said decks so as to lie above and below the same in a plane substantially vertical thereto and where said scrapers extend transversely of said decks into proximity with the vertically extending flanges on the upper side thereof.
